UNITED STATES PATENT OFFICE.

HAROLD H. FEBREY, OF NEWARK, NEW JERSEY, ASSIGNOR TO THE AMERICAN STEEL AND WIRE COMPANY, OF NEW JERSEY, A CORPORATION OF NEW JERSEY.

RAIL BOND.

Application filed January 23, 1924. Serial No. 688,008.

This invention relates to rail bonds and more particularly to rail bonds adapted to be secured to the rail by welding by either the electric arc or gas flame methods.

One object of this invention is to provide a novel form of terminal for bonds of this class, in which the parts are mechanically locked together.

Another object is to provide a bond having 10 the novel combination, construction, and design of parts hereinafter described and illustrated in the accompanying drawings.

In the drawings, Figure 1 is a side elevation 15 of a completed bond constructed in accordance with my invention and having the one terminal partly broken away.

Figures 2 and 3 are a side elevation and top plan, respectively, of the short length of standard tube from which the terminal sleeve 20 is formed.

Figures 4 and 5 are a side elevation and top plan, respectively, showing the same tubing expanded to conical shape.

Figure 6 is a top plan of the expanded tube 25 of Figures 4 and 5 flattened ready to receive the conductors.

Figures 7 and 8 are a side elevation and top plan, respectively, of one form of wedge for 30 clamping the bond body conductors within the sleeve.

Figures 9 and 10 are a top plan and an end view, respectively, of a slightly different form of wedge.

Figure 11 is a side elevation showing one end 35 of a bond body inserted in a terminal sleeve with the wedge positioned ready to be forced together.

Figure 12 is a top plan of one of the assembled bond terminals showing the indented portions for locking the sleeve and wedge in assembled position.

Figure 13 is also a top plan of one of the assembled bond terminals, which has been squared, as required for some installations.

Referring more particularly to the drawings, the letter A designates the body of the bond as a whole, which is composed of flexible conductors 2 and 3, and B designates the terminals which are formed on each end of the 50 body A.

The terminals B are each composed of a tapered seamless sleeve 4, into which the ends of the conductors 2 and 3 are projected, and a wedge 5 which is fitted between the conductors 2 and 3 and forced into the sleeve so as

to clamp the conductors against the sleeve and to increase the cross sectional area of the terminal.

The sleeves 4 are adapted to be formed from standard seamless steel or copper tubing cut 60 to short lengths, as shown in Figures 2 and 3, and then expanded to form a tapered member such as shown in Figures 4 and 5 and finally flattened to the shape shown in Figure 6.

The wedge 5 of Figures 7 and 8 may be composed of either copper or steel and may be cast or forged as desired. The wedge 5 is provided with flat side walls and concave end walls 7 and 8 adapted to fit around the conductors 2 and 3 of the body A. 65

After the wedge 5 has been positioned between the conductors 2 and 3 and wedge, conductors and sleeve 4 all pressed or otherwise forced together, as shown in the completed bond, suitable indentations 9 and 10 are preferably formed in the side walls of the sleeve 75 and wedge 5 to lock the assembled parts together.

It will be noted that in the bond of Figure 1 the conductors 2 and 3 project slightly above 80 the upper edge of the wedge 5 and sleeve 4. This construction provides a better bonding connection between the attaching metal and the terminal when the bond is welded to a rail. However the conductor ends may terminate even with or below the upper edge 85 of the sleeve 4 if desired.

In Figure 13 the bond terminal has been squared after it was assembled by pressing it between suitable dies. This construction 90 facilitates the attaching of the bond to the rail by welding according to some methods.

In Figures 9 and 10 a wedge is shown having an outwardly projecting flange 14 extending along one upper side edge, which flange 95 is adapted to project beyond the sleeve 4 and serve as a spacing member to space the bond away from the rail to which it is attached.

Bonds constructed in accordance with this invention may be readily attached to the rails 100 by either electric arc or gas flame welding, and if steel sleeves and wedges are used a better joint may be formed than if they are composed of copper, since the terminal and rail to which it is attached will be composed 105 of like metal.

Due to the fact that the conductors 2 and 3 are separated by the wedge 5 they will be spaced apart adjacent the lower end of the sleeve 4, as at 15, thereby relieving the con- 110

ductors of any pressure at the point where they enter the sleeve.

The present invention provides a novel form of bond, the parts of which are mechanically secured against displacement and which is adapted to be further secured together by the welding action of the attaching metal when the bond is applied to a rail.

I claim—

- 10 A rail bond adapted to be welded to a rail, comprising a body portion composed of a plurality of round flexible conductors, and terminals formed on each end of said body portion, each of said terminals comprising a
- 15 seamless-elongated sleeve into which the ends of said conductors project, said sleeve having its end walls converging, and a metallic

wedge member having concave end walls which converge on an angle equal to the converging angle of the end walls of said sleeve, 20 radius of the concavities in the end walls of said wedge being equal to that of said conductors said wedge member being forced into said sleeve between said conductors so as to have its concave end walls fitted around said conductors and force said conductors outwardly against the converging end walls of said sleeve, said wedge member being adapted to clamp said conductors in said sleeve and to increase the cross-sectional area of metal in 30 said terminal.

In testimony whereof I have hereunto set my hand.

HAROLD H. FEBREY.
